UNITED STATES PATENT OFFICE.

VICTOR T. KISSINGER AND ARTHUR TRUNKEL, OF CHICAGO, ILLINOIS.

ELECTRIC SIGNAL SYSTEM.

SPECIFICATION forming part of Letters Patent No. 629,792, dated August 1, 1899.

Application filed June 5, 1899. Serial No. 719,356. (No model.)

To all whom it may concern:

Be it known that we, VICTOR T. KISSINGER and ARTHUR TRUNKEL, citizens of the United States, residing at Chicago, in the county of Cook and State of Illinois, have invented certain new and useful Improvements in Electric Signal Systems, of which the following is a specification, reference being had to the accompanying drawing, forming a part thereof.

10 This invention relates particularly to district-telegraph systems. Its main objects are to automatically transmit from various points to a central point or station signals indicating the points or boxes where they originate and generally to improve the construction and operation of apparatus of this class.

It consists in certain novel features in the construction and arrangement of component parts of the apparatus, as hereinafter particularly described, and pointed out in the claims.

The accompanying drawing is a diagram of apparatus embodying our invention.

A designates a source of electricity, which may be a battery or other electric generator. 25 1, 2, and 3 are wires or conductors constituting a metallic circuit which is connected with one pole *a* only of the generator, the other pole *a'* of which has a ground connection. This circuit being normally closed and 30 continuous may be easily tested for breaks, grounds, or crosses. One part 3 of this circuit includes the coils of a relay-magnet *B*, which controls a local circuit 4, provided with a battery *C* or other suitable electric generator, and a register *D* or other suitable device 35 for recording or receiving signals. The relay, local circuit, and register or receiving apparatus, with their accessories, may be of the usual or any suitable construction and arrangement for the purpose and of themselves do not constitute invention.

E E' designate call-boxes or signal-transmitting devices which are arranged in series with each other and with one pole of the generator *A* in the main circuit 1 2 3. The several call-boxes, as shown, being of the same construction and arrangement, it will be sufficient to describe one of them in detail.

F, G, and H designate, respectively, a 45 ratchet-wheel, a break-wheel, and a notched disk, which may be, and are preferably, mounted upon the same shaft and suitably

insulated from the frame or case in which said shaft has its bearings.

I is an electromagnet, the armature of which is carried by a spring-retracted armature-lever *J*. One arm of this lever is provided with a pawl or dog *f*, which engages with the teeth of the ratchet-wheel *F*. The other arm of said lever is provided with an insulated spring *j*, which normally engages a contact 5.

g is a spring-contact adapted by engagement with the teeth of the break-wheel *G*, when the latter is turned, to successively close 65 the signal-transmitting circuit, and thereby indicate on the register *D* or other receiving apparatus at the central station the number of the box by which the signal is sent, the break-wheels of the several call-boxes in the 70 system having teeth varying in number or arrangement, so as to distinguish the signals produced thereby.

h is a spring or pivoted arm, the free end of which is insulated or formed of insulated 75 material and projects normally into the notch in the disk *H*.

6, 7, 8, and 9 are contact-springs insulated from each other, the two intermediate springs 7 and 8 being extended at their free ends and 80 bent laterally, so as to be engaged by the insulated end or portion of the arm *h* when the latter is pressed outward by the rotation of the disk *H*. When the mechanism of the call-box is at rest, with the end of the arm *h* 85 in the notch of the disk *H*, the contacts of the springs 6 and 7 will be in engagement, but the contacts of the springs 8 and 9 will be separated, as shown at the right in the drawing.

K designates a push-button or circuit-controller placed on the call-box or in any convenient location at a distance therefrom. One contact of the push-button is electrically connected with the contact-spring 9, the break-wheel *G*, and, through the winding of 95 the magnet *I*, with the contact 5. The other contact of the push-button has a ground connection 10. The contact-springs *j* and 7 are connected with one wire or terminal and the contact-springs *g* and 6 are connected with 100 the other wire or terminal of the main line. The contact-spring 8 has a ground connection.

The ratchet-wheel *F*, pawl *f*, magnet *I*, and armature-lever *J*, with their adjuncts, con-

stitute an electromagnetic motor for turning the break-wheel G and disk H.

The apparatus hereinbefore described operates as follows: Assuming that an alarm or signal is to be sent in from the box designated E, the push-button K or circuit-controller associated with that box is pressed or operated to close the ground connection of the magnet I, as shown at the left in the drawing. When this is done, current passes from pole a of the generator through the wire 1, spring j , contact 5, magnet I, and contacts of the push-button K to ground 10, and thence back to the other pole a' of the generator through its ground connection. The magnet I being thus energized attracts its armature, turning the lever J on its fulcrum against the tension of its retracting-spring and operating through the pawl f to turn the ratchet-wheel F and the connected break-wheel G and disk H an interval. The foregoing movement of the armature-lever J carries the spring j out of engagement with the contact 5, thus momentarily breaking the circuit through said magnet. The lever J being released by the magnet is withdrawn by its retracting-spring and carries the contact-spring j back into engagement with the contact 5, thereby closing the circuit through said magnet. A rapid vibration is thus imparted to the lever J, which turns the break-wheel G and disk H to the left, as indicated by the arrow. The ground connection of the magnet I is manually held closed by the push-button or circuit-controller K until the disk H has been turned sufficiently to carry the notch therein away from the adjacent end of the arm h , which is forced to the right by engagement with the periphery of said disk, thereby carrying the contact-spring 7 out of engagement with the contact-spring 6 and the contact-spring 8 into engagement with the contact-spring 9. The push-button may now be released, and the ground connection of magnet I will be maintained through the contact-springs 8 and 9 until the disk H has made a complete revolution and the end of the arm h drops into the notch therein. When this occurs, the ground connection of the magnet I is broken and the mechanism is automatically stopped after sending in a complete signal, which is produced by one revolution of the break-wheel. As the teeth of the break-wheel successively pass and engage with the contact-spring g the signal-transmitting part of the circuit is closed and current flows from one pole a of the generator through the winding of the relay-magnet B, wire 3, contact-springs 6 and 7 of the call-box E', wire 2, contact-spring g of the call-box E, break-wheel G, and contact-springs 8 and 9 to ground 10, and thence back to the other pole a' of the generator through its ground connection. A series of impulses corresponding with the number of teeth on the break-wheel of the call-box E is thus transmitted through the relay-magnet B, which by successively closing the local cir-

cuit 4 produces therein a corresponding series of impulses, which is recorded or indicated by the register or receiving instrument 70 D, thereby designating the number of the box from which the alarm or signal is sent in. When the mechanism of any call-box in the system is at rest, the circuit is maintained through the contact-springs 6 and 7 of that box for the transmission of signals from other boxes. When any call-box of the system is grounded, two separate circuits are thereupon established between that box and the generator at the central station—one for the operation of the electromagnetic motor and the other for the transmission of the signal, one circuit including the magnet I of the motor and the other the relay-magnet B. One battery or generator, located at the central station with the relay local circuit and receiving instrument, supplies current not only for actuating the signal-transmitting mechanism of the several call-boxes included in the system, but also for transmitting the signals therefrom. 90

Various changes in the minor details of construction and arrangement of parts of the apparatus may be made without departing from the spirit and intended scope of our invention. 95

We claim—

1. In an electric signal system the combination with an electric generator, of a metallic circuit connected with one pole of said generator, the other pole of which has a ground connection, a number of signal-transmitting devices included in said circuit and each comprising a break-wheel, a co-operating contact connected with one part of the main line, and an electromagnetic motor for turning said break-wheel connected with the other part of the main line, and having a manually-controlled ground connection, substantially as and for the purposes set forth. 100

2. In an electric signal system the combination with an electric generator, one pole of which has a ground connection, a continuous metallic circuit connected with the other pole of said generator and signal-receiving apparatus, of signal-transmitting apparatus comprising a break-wheel, a contact co-operating therewith and connected with the side of said circuit containing the receiving apparatus, an electromagnetic motor for turning said break-wheel, connected with the other side 110 of said circuit and having a ground connection, a manually-operated circuit-controller in said ground connection, and an automatic circuit-controller operated by said signal-transmitting mechanism in a ground connection of both the motor and break-wheel, substantially as and for the purposes set forth. 115

3. In an electric signal system the combination with an electric generator having a ground connection on one side, a normally unbroken metallic circuit connected with the other side of said generator, and signal-receiving apparatus connected with said circuit, of signal-transmitting devices connected in se- 120

ries by said circuit and each comprising a break-wheel, a coöperating contact connected with one part of said circuit, an electromagnetic motor for turning said wheel, connected with the other part of said circuit, a pair of contacts connected respectively with the two parts of said circuit and normally short-circuiting the associated signal-transmitting mechanism, another pair of normally separated contacts, one connected with said motor and break-wheel and the other with the ground, said signal-transmitting mechanism being constructed and arranged to separate the first pair of contacts and to close the second pair when the break-wheel is started, and a manually-operated circuit-controller in a ground connection of said motor, substantially as and for the purposes set forth.

4. In an electric signal system the combination with an electric generator one pole of which is connected with the ground, a normally closed metallic circuit connected with the other pole of said generator, and signal-receiving apparatus connected with a part of said circuit, of a number of signal-transmitters included in series in said circuit and each comprising a break-wheel, a contact adapted to coöperate therewith and connected with one part of said circuit, a notched disk adapted to turn synchronously with said break-wheel, an electromagnetic motor for turning said wheel and disk, connected with the other part of said circuit, a pair of normally engaging contacts connected respectively with the two parts of said circuit, another pair of normally separated contacts, one connected with said motor and break-wheel and the other with the ground, said disk being constructed and arranged when turned to separate the first pair of contacts and to close the second pair and

to hold them in that relation until the notch in said disk returns to its starting-point, thereby permitting said contacts to resume their original relations to each other, and a manually-controlled ground connection for starting 45 said motor, substantially as and for the purposes set forth.

5. In an electric signal system the combination with an electric generator having one pole grounded, and a normally closed metallic 50 circuit connected with the other pole of the generator, of signal-transmitting devices each comprising a break-wheel, a coöperating contact connected with a part of said circuit, an electromagnetic motor for turning said break-wheel, consisting of a ratchet-wheel, a spring-retracted armature-lever carrying a pawl in engagement with said ratchet-wheel and provided with an insulated spring which is connected with the other part of said circuit, a 55 contact with which said spring normally engages, an electromagnet having its winding connected at one end with said contact and at the other end with a normally open ground connection, means for manually closing said 60 ground connection, and means operated by the signal-transmitting mechanism for maintaining a ground connection with said magnet and break-wheel while the latter makes a revolution, and for breaking said ground connection 65 70 when said break-wheel has completed its signal, substantially as and for the purposes set forth.

In witness whereof we hereto affix our signatures in presence of two witnesses.
